EJECTOR FOR POWER PRESSES

Edmund W. Zeh, Newark, N. J.

Application March 5, 1931, Serial No. 520,324

7 Claims. (Cl. 78—13)

This invention relates in general to that class of power presses in which a head for carrying one die is moved toward and away from a bed supporting a fixed die by a screw which is alternately rotated in opposite directions by alternate engagement of a pair of friction disks with opposite sides of a friction wheel carried by the screw, the invention being more particularly directed to large presses of this type utilized for operations wherein the work may become stuck upon the die carried by the head, for example, in die forging operations. In such presses, the return or upward movement of the head and upper die is not uniform; in other words, the head sometimes moves farther on the return movement than at other times, due to the momentum of the friction wheel and slight variations in the braking thereof.

One object of the invention is to provide novel and improved means for stripping or ejecting work from the die carried by the head of a power press, whereby quick and positive ejection of the work from the die is ensured.

Another object is to provide an ejector or die stripper of the general character described especially adapted for use with power presses of the particular type described, so that the ejector shall be actuated only a predetermined distance regardless of variations in the return or upward movement of the head of the press. In other words, the invention particularly contemplates a die stripper or work ejector of this character embodying novel and improved features of construction which shall compensate for non-uniform return movement of the head of the press.

A further object of the invention is to provide an ejector for power presses embodying novel and improved features of construction, whereby ejecting pressure shall be exerted upon the work uniformly at a plurality of points to ensure easy and positive stripping or ejecting of the work from the die.

Other objects are to provide such an ejector comprising a plurality of ejecting members or plungers mounted in the head of the press, and means for simultaneously and uniformly actuating all of said plungers; to provide such apparatus which shall be simple, inexpensive and reliable in construction and operation; and to obtain other advantages and results as will be brought out by the following description.

Referring to the accompanying drawings, in which corresponding and like parts are designated throughout the several views by the same reference characters,

Figure 1 is a front elevation of a power press having an ejector embodying my invention, showing the parts with the dies separated and the work being ejected;

Figure 2 is a fragmentary front elevation of the press showing the dies in engagement to operate upon the work;

Figure 3 is a fragmentary enlarged horizontal sectional view, on the line 3—3 of Figure 2;

Figure 4 is an enlarged fragmentary transverse vertical sectional view, on the line 4—4 of Figure 2;

Figure 5 is a fragmentary transverse vertical sectional view, on the line 5—5 of Figure 3, showing the dies separated and the work being ejected from the die;

Figure 6 is a similar view, on the line 6—6 of Figure 3, portions being broken away;

Figure 7 is a fragmentary transverse vertical sectional view through the head of the press showing a modification of the invention, and

Figure 8 is a view similar to Figure 5 showing a further modification.

The invention is specifically described in connection with a known type of screw power press which includes a frame 1 that is provided with an elongated vertically disposed opening 2 extending transversely through the frame at its longitudinal center, said opening being formed at the lower end with a bed 3 upon which is fixed a die 4. The sides of the opening 2 are provided with vertical guides 5 upon and between which is mounted a vertically slideable head 6 upon which is mounted a die holder 7 carrying a die 8 to cooperate with the fixed die 4 for producing a die forging A. The exact form of the dies is immaterial to the invention, and varies according to the work to be produced, but in the present instance the die 4 has a recess 9 into which the die 8 is movable to compress heated metal for forming the cup-shaped forging A.

The head 6 is carried by the lower end of a vertical screw 10 which has a suitable swivel connection with the head and extends upwardly through the top of the frame 1, the upper end thereof being provided with a horizontally disposed wheel 11 having a friction surface on its periphery. It is obvious, therefore, that rotation of the screw alternately in opposite directions will cause the head to be moved up and down on the guides 5.

Arranged above the friction wheel 11 and diametrically thereof is a horizontally disposed drive shaft 12 journaled in bearings 13 and 14 at the upper ends of upstanding brackets 15 and 16 11e

secured to opposite sides of the frame. The bearings 13 and 14 are preferably antifriction, and the shaft 12 is both rotatable and slideable therein. Fixed on the shaft 12 at diametrically opposite sides of the friction wheel 11 is a pair of friction disks 17 and 18 adapted to alternately engage the friction surface of the wheel 11 to rotate the screw 10. The disks have the respective pulleys 19 and 20, which are adapted to receive drive belts (not shown) to rotate the shaft 12. Assuming the shaft 12 to be rotating in the direction of the arrows on Figures 1 and 2, it will be obvious that as the friction disk 17 engages the wheel 11 the head 6 will be forced downwardly, while engagement of the disk 18 with the wheel 11 will move the head 6 upwardly. To accomplish the alternate engagement of the friction disks 17 and 18 with the friction wheel 11 the shaft 12 is slideable in its bearings, and is preferably actuated by a fluid pressure motor 21 controlled by a valve, or by other suitable means, not shown.

With this construction, it will be observed that the die forging or other work may be produced by cooperation of the dies 4 and 8 which is caused by reciprocation of the head 6, the work being removed from the dies when the head 6 moves on its upward or return stroke.

Frequently the work A shrinks and becomes stuck or jammed upon the upper die 8 so that the work moves upwardly with the die and does not become released therefrom. The present invention is directed toward a stripping or ejecting apparatus to positively remove the work from the upper die 8. This apparatus includes a plurality of knockout plungers 22 vertically slideable in openings 23 in the head 6 and arranged transversely thereof in the same plane. These plungers 22 are simultaneously reciprocated by any suitable means, for example, as shown in Figure 5 of the drawings, by a long pinion 24 journaled to rotate about a horizontal axis in an opening 240 in the head 6 and meshing with rack teeth 25 upon each of the plungers. The pinion 24 projects from the head 6 at the front thereof and has connected thereto a crank arm 26 having a roller 27 on one end. This crank arm is normally influenced by suitable means, such as a spring 28, into an approximately horizontal position, as shown in Figure 2 of the drawings, so as to move the plungers 22 upwardly in their openings 23. Movement of the crank arm in this direction is limited by a stop lug 29 which engages a boss 30 on the head 6.

Within the path of movement of the crank arm 26 as the head 6 moves up and down and intermediate the limits of movement of said head, is an abutment track 31 secured to the frame of the press and having a horizontal portion 32 which lies in the path of movement of the roller 27 so as to be engaged momentarily thereby to oscillate the crank arm when the head 6 is raised and lowered. The track 31 has another portion 33 disposed substantially vertically and at an angle to the portion 32. When the head is in its lower position, as shown in Figure 2 of the drawings, the crank arm 26 clears the track 31 and the roller 27 lies under the portion 32 of the track. As the head moves upwardly, the roller 27 engages the portion 32 of the track so that the crank arm is rotated downwardly in the direction of the arrows shown in Figure 1 of the drawings, which results in the plungers 22 being slid downwardly in their openings 23. The roller 26 may then follow the vertical portion 33

of the track without further rotation of the crank arm, so that regardless of slight variations in the extent of upward movement of the head 6, the plungers 22 will be slid downwardly only a predetermined distance. 80

The plungers 22 actuate a stripper plate 34 which is mounted on rods 35 vertically slideable in the die holder 7. This stripper plate has an opening 36 to nicely slide upon the die 8 and is normally held snugly against the lower end of the die holder by compression springs 37, so as to clear the end of the die and leave the latter free to operate with the lower die 8, as shown in Figure 4 of the drawings. Each of the rods 35 is in alignment with and abuttingly engaged by one of the plungers 22, as clearly shown in Figures 4 and 5 of the drawings.

In operation, when the dies are brought into work-forming relation, as shown in Figure 4 of the drawings, the stripper plate is arranged between the dies and in tight engagement with the lower end of the die holder 7. As the head 6 moves upwardly and the roller 27 engages the track 32, the plungers 22 are forced downwardly and in turn push the rods 35 downwardly so as to slide the stripper plate downwardly upon the die 8 and force the work A from the die, as clearly shown in Figures 5 and 6 of the drawings. 95

It will be observed that the pressure is applied to the stripper plate at diametrically opposite sides thereof so that the pressure is balanced and uniform, and the plungers 22 are simultaneously actuated, so that there is a positive and uniform pressure exerted on all parts of the work whereby it is easily and quickly dislodged from the upper die 8. It will also be observed that the action is like that of a hammer; in other words, when the roller 27 strikes the track 31, the stripper plate is quickly pushed downward. 100

Other means than the rack and pinion 24, 25 for actuating the plungers, may be utilized. For example, as shown in Figure 8 of the drawings, each plunger may be provided with a notch 38 engaged by the end 39 of a crank 40 mounted on a shaft 41 which is rotatable like the pinion 24. 110

Furthermore, any desired number of plungers 22 may be utilized, according to the work to be produced in the press, and in Figure 7 of the drawings I have shown three plungers. 120

From the foregoing, it will be understood that the stripper plate 34 is moved downwardly into die-stripping position as the head of the press moves upwardly to separate the dies, and is held in this position by the track 33 until the head next moves downwardly, and that the stripper plate is actuated only a predetermined distance regardless of the extent of return movement of the head 6, so that there is no possibility of damage to any of the parts by overthrow of the return movement of the head. The plurality of plungers 22 provides for flexibility in the adaptation of the press to various types of work, and also enables uniform ejecting pressure to be applied to the work at a plurality of points. The shape and size of the stripper plate obviously may be varied in accordance with the kind of work and the dies, and may be separably connected to the rods 35. 130

Other modifications and changes in the details of construction of the apparatus will appear to those skilled in the art without departing from the spirit or scope of the invention, and therefore I do not desire to be understood as limiting myself in the construction and use of the invention except as required by the following claims when construed in the light of the prior art. 145 150

Having thus described the invention, what I claim is:

1. In a press, the combination with a frame to receive a fixed die, a head reciprocable in said frame to receive a die to cooperate with said fixed die, and means for reciprocating said head to cause engagement and separation of said dies, of means for ejecting work from the die on said head including a plurality of reciprocating plungers on said head each having a rack thereon, a member to oscillate on said head, a pinion journaled in said head and connected to said member and meshing with said racks of all of said plungers to simultaneously reciprocate said plungers upon oscillation of said member, and means for oscillating said member alternately in opposite directions upon movement of said head in opposite directions respectively. 80
2. In a press, the combination with a frame to receive a fixed die, a head reciprocable in said frame to receive a die to cooperate with said fixed die, and means for reciprocating said head to cause engagement and separation of said dies, the extent of movement of said head to separate said dies being variable, of means for ejecting work from the die on said head including a plurality of cooperating parts one of which is a knockout plunger to eject work from the die and the other of which is a movable member 90
- 30 mounted on said head to actuate said knockout member, and an abutment means including an abutment to be engaged momentarily by said movable member at a predetermined point in the movement of said head in a direction to separate said dies and actuate said movable member a predetermined distance to move said knockout plunger a predetermined distance to eject work from said die on the head, said abutment means including a track beyond said abutment over 100
- 40 which said movable member may idly move with said head in said direction beyond said predetermined point in the movement of the head without further actuation of said knockout plunger, whereby excessive ejecting movement of said knockout plunger and excessive strain on said ejecting means as a result of variations in extent of movement of said head in said direction are prevented. 110
3. The press set forth in claim 2, with the addition of means for returning said movable member and said knockout member to their normal positions when said movable member passes said abutment during movement of said head in the direction to cause engagement of said dies. 120
4. The press set forth in claim 3 with the addition of yielding means for normally influencing said actuating member in the direction opposite to that in which said actuating member is moved by said abutment. 130
5. In a press, the combination with a frame to receive a fixed die, a head reciprocable in said frame to receive a die to cooperate with said 140

fixed die, and means for reciprocating said head to cause engagement and separation of said dies, the extent of movement of said head to separate said dies being variable, of means for ejecting work from the die on said head including a reciprocating knockout plunger on said head having a rack thereon, a member to oscillate on said head, a pinion journaled on said head and connected to said member and meshing with said rack to reciprocate said plunger upon oscillation of said member, and an abutment located intermediate the limits of movement of said actuating member with said head to be engaged momentarily by said member as said head moves in the direction to separate said dies so as to actuate said member and move said knockout plunger a predetermined distance to eject work from said die on the head, said member being movable with said head in said direction past and out of engagement with said abutment, whereby excessive ejecting movement of said knockout plunger and excessive strain on said ejecting means as the result of variations in the extent of movement of said head are prevented. 150

6. The press set forth in claim 5 with the addition of yielding means normally influencing said member in the direction opposite to that in which said member is actuated by said abutment. 160

7. In a press, the combination with a frame to receive a fixed die, a head reciprocable in said frame to receive a die to cooperate with said fixed die, and means for reciprocating said head to cause engagement and separation of said dies, the extent of movement of said head to separate said dies being variable, of means for ejecting work from the die on the head including a knockout plunger, an actuating member therefor movably mounted on and movable with said head and having a lateral crank arm, an operative connection between said plunger and said actuating member for actuating said plunger upon movement of said actuating member on said head, and an abutment located intermediate the limits of movement of said actuating member with said head and at one side of the actuating member in the path of movement of said crank arm to be engaged momentarily by said crank arm of said actuating member as said head moves in the direction to separate said dies so as to actuate said actuating member to move said knockout plunger a predetermined distance and eject work from said die on the head, said actuating member being movable with said head in said direction to move said crank arm past 170 and out of engagement with said abutment so that further ejecting movement of said knockout plunger and excessive strain on said ejecting means during further movement of said head in said direction are prevented. 180

EDMUND W. ZEH.
